UNITED STATES PATENT OFFICE

ROY M. SMITH, OF NORTH ARLINGTON, NEW JERSEY, ASSIGNOR TO WESTINGHOUSE ELECTRIC & MANUFACTURING COMPANY, A CORPORATION OF PENNSYLVANIA

INDUCTION RELAY

Application filed November 13, 1929. Serial No. 406,816.

My invention relates to induction relays and particularly to means for modifying the relation of the phase-displaced actuating fluxes of current-responsive relays.

One object of my invention is to provide a device of the above-indicated character that shall provide relatively great phase displacement of its actuating fluxes.

Another object of my invention is to provide an induction relay in which the phase displacement of its actuating fluxes, and thereby its operating torque, is not reduced at its high-current operating values.

Another object of my invention is to provide a self-contained induction relay unit in which the phase-displacement of its actuating fluxes is increased without recourse to external apparatus, such as resistors.

A further object of my invention is to provide a relay or equivalent structure that shall be simple and durable in construction, economical to manufacture and effective in its operation.

In induction relays of the current-responsive type, it has heretofore been usual to employ a single means, such as a closed-circuit coil or loop, on the main flux-pole portion of the field-magnet core to increase the range of movement of the armature over which it has torque effective to actuate contact members.

In such a device, while the flux-phase displacement is improved, it is not the maximum to which a relay of comparable size is capable, as evidenced by a suggestion calling for the use of an external resistor in shunt relation to the relay winding.

However, the latter device, in addition to the external resistor, or separate apparatus, which destroys the identity of the relay as a single self-contained unit, has the further disadvantage of losses caused by the resistor.

It is my aim to retain the identity of a current relay of the induction type as a compact self-contained unit and at the same time, to take advantage of the ability of the relay to utilize its torque capabilities to substantially a maximum in accordance with its size and space limitation, without undue loss.

Accordingly, in practicing my invention, I provide an induction relay of the current-re-

sponsive type in which a plurality of relatively small closed-circuit coils or loops, of a type heretofore used singly, are so disposed as to attain the aim and objects of my invention without undue loss and without the sacrifice of the identity of the device as a self-contained unit. 55

Figure 1, of the accompanying drawings, is a diagrammatic view of a current-responsive relay embodying my invention, 60

Fig. 2 is a perspective view of the field-magnet core of the relay, showing the type and position of the closed-circuit elements by which the results of my invention are attained, 65

Fig. 3 is a polar diagram, showing the flux phase displacements obtained by the use of the closed-loop elements severally and together, and

Fig. 4 is a circuit diagram illustrating one application or use of the invention. 70

Referring to Fig. 1, the device comprises, in general, a field-magnet core 2, an armature 3, a main or primary energizing current winding 4, secondary coils 7, a closed-circuit coil or loop element 9 and a closed-circuit coil, loop or lag element 10. 75

The core member 2, shown more clearly in Fig. 2, is of a type commonly employed in watt-hour meters and consists of a stack of flat-plane iron laminations. It is in the form of a frame or loop having a portion 11 extending entirely around its perimeter in the plane of the laminations, a main inwardly-projecting pole portion 12 centrally disposed between side portions 14 which merge into laterally-projecting side pole portions 15 disposed in spaced relation to the sides of the free end of the main pole portion 12 and into oppositely-projecting portions 16 of the 85 peripheral portion 14 at one side of the armature 3.

The portions 16 intercept side portions 17 that support a cross portion 18 which has a pair of pole portions 20 extending in the direction of the main pole portion 12 at the opposite side of the armature 3. 95

The armature 3 is preferably constructed as an aluminum disk, of usual form in watt-hour meters, that is mounted on a spring. 100

constrained shaft and is adapted to actuate contact members. The shaft, the spring, or other biasing means, the contact members and other elements, being of usual and well-known character, are omitted as not necessary to a full understanding of the invention.

The current winding 4 takes the place of the usual watthour-meter voltage winding on the main pole portion 12 and is energized 10 from a desired current source, through leads 21 and terminals 22.

Viewing the device as illustrated in Fig. 1, if the closed-circuit elements 9 and 10 are both omitted, there are fluxes supplied by the 15 coils 9 and 7 which are in sufficiently displaced phase relation to turn the armature disk 3, as in a watthour meter. If not constrained, the disk rotates but, if constrained, as by a spring, the disk turns against the 20 constraining force by any desired amount within limits. It is the latter effect which is utilized in relays to close and open contact-making-and-breaking devices to protect a circuit against current overloads or to actuate 25 a switch or other device in response to any predetermined current value in the winding 4.

However, without the closed-circuit loop 9 or 10, the phase displacement of the co- 30 acting fluxes from the coils 4 and 7, respectively, is relatively small and the operating range of the instrument on which an effective contact-closing torque is obtained is also small.

35 It has been suggested, prior to my invention, to employ one or the other of the closed-current loops 9 and 10 in a position similar to that illustrated for each but, to the best of my knowledge, it has never before been suggested to employ both elements 9 and 10 at 40 the same time or in the one structure or relay.

In Fig. 3 is illustrated, in polar co-ordinates, the total phase-displacement of the actuating fluxes as effected by the closed-circuit elements 9 and 10 severally and together.

The curve marked "Loop 9" represents the phase displacement caused between the co-operating fluxes by the loop 9 by the distance it is rotated from the reference vector in the 50 clockwise direction about the base of this vector. By observing the projection of this curve on the base line marked "Current units", it is seen that, for small current values, the phase-displacement between the 55 fluxes increases rapidly for only a relatively short increase of current and thereafter approaches zero.

The curve marked "Loop 10" represents a 60 substantially constantly increasing displacement in the phase-relation of the fluxes but this displacement is limited in its total value by the size or physical character of the instrument. Irrespective of the latter factor, when both loops 9 and 10 are employed, as 65 shown, the total flux phase displacement is

as represented by the curve marked "Loops 9 and 10", combining the displacements of the loops 9 and 10 severally in such manner as to obtain a very materially improved characteristic for the instrument.

By this means, the torque of the armature is increased over a considerably greater range, in an extremely simple, expeditious and economical manner, without destroying the identity of the relay as a compact self-contained unit, without the use of extraneous apparatus and without the losses caused by such apparatus.

As illustrated in Fig. 4, two relays 24 and 25, each of the construction above described, 80 are associated with branch circuits 27 and 28, respectively, of a main circuit 29, the windings 7 being connected to current transformers 30 and 31 and the windings 9 being connected to a current transformer 33. The 85 latter is associated with the grounded neutral lead 35 of a polyphase transformer 36 that is connected to the circuit 29.

The circuits are such that a ground in either of the circuits 27 or 28 will cause the 90 corresponding relay to operate to trip a circuit interrupter (not shown) in the grounded circuit without interfering with the operation of the other circuit.

While I have shown and described a particular form of my invention, changes may be effected therein without departing from the spirit and scope thereof, as set forth in the appended claims.

I claim as my invention:

1. In an induction-type relay having a rotatable armature member, main and secondary poles cooperating therewith, an energizing winding on said main pole and a winding on said secondary poles inductively related to said energizing winding, means for lagging the total flux in said main pole including a plurality of short-circuited conductors cooperating with said main pole and main energizing winding.

2. In an induction instrument having a rotatable armature member, a field-magnet core having a main pole and secondary poles cooperating with opposite sides of said armature member, respectively, an energizing winding positioned on said main pole and a winding on said secondary poles inductively related to said energizing winding, means for effecting the maximum lag of the total flux in said main pole comprising a closed 115 conducting loop positioned on said main pole adjacent said armature member and a short-circuited turn positioned on said main pole displaced from said closed conducting loop.

In testimony whereof, I have hereunto subscribed my name this 8th day of November, 1929.

ROY M. SMITH.
